DETACHABLE LADDER-HOOK.

1,030,905.

Specification of Letters Patent.

Patented July 2, 1912.

Application filed October 25, 1911. Serial No. 656,774.

To all whom it may concern:

Be it known that I, HOWARD M. LUCAS, formerly of Watertown, Jefferson county, New York, a citizen of the United States, residing at Gatun, Canal Zone, Panama, have invented certain new and useful Improvements in Detachable Ladder-Hooks, of which the following is a specification.

This invention relates to detachable ladder hooks, designed for use in connection with fire and other ladders, and has for its object to provide a novel, simple, convenient and inexpensive attachment for ladders, whereby any of the ordinary fire ladders may be converted into what is known as roof or scaling ladders, and the said hooks may be applied to, and removed from the ladders, or transferred from one ladder to another in a quick and ready manner.

20 And a further object is to provide means for adjusting the said hooks to ladders of different sizes.

Other features and parts of the invention will be understood from the detailed description which follows, and by reference to the accompanying drawing which forms a part of this specification, and in which—

Figure 1 is a face view of a ladder, having my improvement applied thereto. Fig. 2 is a sectional view; showing the hooks interlocked with the ladder. Fig. 3 is a similar sectional view; showing the hooks partially detached. Fig. 4 is an enlarged detail view, illustrating the adjustable parts. Fig. 5 is a perspective view of the detachable hooks. Fig. 6 is an elevational view; showing a modified form of the device.

Similar characters of reference are assigned to corresponding parts throughout the several views.

Heretofore, most of the roof and scaling ladders used by the fire departments have been fitted with hooks permanently attached to the ends of the ladders, and therefore not capable of being detached, or transferred from one ladder to another. Under this old arrangement, whenever either the ladders or the hooks become broken or impaired, the department is without means of 45 restoring the said equipment except by obtaining new ladders.

It is a particular object of the present invention to provide novel and simple detachable hooks, which are capable of being readily and quickly applied to any of the ordi-

nary fire ladders in a few moments' time, and which are also capable of being transferred from a damaged to a perfect ladder without requiring any alteration or change in the ladder or in the hooks.

60 A description of my detachable hooks follows:

In the drawing 2 represents the side rails of a ladder, and 3 the series of rounds which connect the rails together in the usual manner.

65 My improved device consists of a pair of like side pieces, or arms 4, which are connected together and held parallel with each other, by means of a cross-rod 5 which is disposed near the lower ends. The arms 4 are preferably made out of flat wrought metal, and their upper ends are formed with large hooks 6, which have sharp points for positively hooking or attaching the device 70 to the roof, or to the window sills of a building, for temporarily supporting the ladder to which the hooks are applied. The lower ends of the arms or bars 4 are formed into smaller hooks 7 adapted for engaging and 75 gripping one of the rounds 3 of the ladder. The hooks 7 are preferably formed on the same side of the arms 4 as the hooks 6, and the arms 4 when connected up ready to be applied to the ladder, are intended to lie 80 between, and to be disposed substantially flush with one edge of the rails 2 of the ladder. The hooks 7 preferably engage and grip the second round from the end of the ladder, as shown in the drawing. To secure the detachable hooks to the ladder, I 85 provide a swinging catch or clamp, which 90 comprises a pair of like side pieces or bars 8, which are connected and held parallel to each other by cross-rods 9 and 10, and when 95 the parts are assembled, the whole of the catch is intended to fit loosely between the said arms 4. The rod 9 preferably passes through the lower ends of the side pieces 8, and then through the arms 4 of the main 100 hooks, for pivotally connecting the clamp to said arms. The rod 10 passes through the upper ends of the parts 8, and this rod is fitted with a pair of depending perforated lugs 11 which are disposed near the 105 middle of said rod. The lower end of each of the side bars 8 is formed with a laterally and downwardly facing hook 12, which is arranged to engage and grip the topmost round 3 for completing the attachment of 110

the device to the ladder. The hooks 7 of the arms 4, and the hooks 12 of the clamp are preferably spaced so that when the clamp is swung into closed position, as shown in Figs. 1 and 2, all of said hooks are made to tightly grip the adjacent rounds 3, for holding the device in service position. After the catch or clamp is swung into locking position, it is held there by means of oppositely disposed latch-bolts 13 and 14, the inner ends of which pass through the perforated lugs 11 of the rod 10, while the outer ends of the said bolts pass loosely through perforations 15 and 16 formed respectively in the side bars 8 and the arms 4. Bolts 13 and 14 are provided with depending grip lugs 17, which are disposed near the inner ends, and which are employed for withdrawing the said bolts from the perforations in the bars 4 of the hooks, when it is desired to release the clamp and swing the said part away from the upper round 3, as shown in Fig. 3. To release the bolts 13 and 14 simultaneously the operator should grasp the lugs 17 with thumb and finger and press them together. The said bolts are provided with coil-springs 18, which exert their tension for holding the bolts interlocked with the arms 4. To apply the device to a ladder, the small hooks 7 are first hooked over the second round 3, as shown in Fig. 3, and then the whole device is swung toward the ladder until the arms 4 contact with the upper round 3, when the clamp may be swung from the position shown in Fig. 3 to that shown in Fig. 2, which brings the hooks 12 into engagement with the said round, as best seen in Fig. 2. When the clamp is swung inwardly until its side bars 8 coincide with the arms 4 and the rails 2, the latch bolts 12 and 13 will be forced by the tension of the springs 18 into the perforations 16 of the bars 4, which will effect the locking of the clamp.

Practically all fire ladders are so constructed that the rounds for the different sized ladders have the same spacing and the spacing of the rounds throughout the length of each ladder is substantially the same. It frequently happens, however, that after the ladders are made and become seasoned, there is a slight variation in the spacing of the rounds of the different ladders, and sometimes in the same ladder, due to the expansion or contraction of the wood, of which the ladders are made. For this reason some means of adjustment is required in order to properly and safely apply my detachable hooks. To this end I provide adjustable parts comprising blocks 19 which are slideable in the hooks 7 of the arms 4, the said blocks being held in place by side lugs 20. The upper faces of the said blocks have semi-circular notches or grooves to receive or engage the rounds. 21 represents the ad-

justing screws which pass through threaded holes in the hooks 7 and their upper ends are swiveled to the blocks 19, as shown in Fig. 4.

It is obvious that the securing hooks and also the clamping parts may be arranged in the reverse order, as illustrated in Fig. 6, and that other changes and modifications may be made in the device, without departing from the spirit of my invention, and I therefore do not restrict myself to the precise construction, arrangement and operation as herein shown and described.

Having thus described my invention, what I claim, is—

1. The combination with a ladder, of a pair of arms connected and held parallel to each other, one end of said arms formed into scaling hooks, the opposite ends of said arms formed into hooks adapted to engage a round of the ladder, a clamping part comprising parallel bars connected together, each of said bars having laterally and downwardly facing hooks for engaging the next round in the ladder, and means for pivotally connecting the said clamp to the said arms.

2. A detachable ladder hook, comprising parallel arms having small hooks at one end adapted to grip a round of the ladder, and having large hooks at their opposite ends adapted for attaching the ladder to the roof or other part of a building, a swinging catch pivoted between said arms, adapted to grip the topmost round of the ladder for interlocking the device with the ladder, and a pair of spring controlled latch-bolts for locking the catch to said arms.

3. Detachable ladder hooks, comprising parallel arms capable of being disposed between the rails of a ladder, one end of said arms overhanging the end of the ladder, and formed into "scaling" hooks, the opposite ends of said arms adapted to grip a round of the ladder, a pivoted clamp disposed between said arms, adapted to grip a round between said first round and the end of the ladder for locking said hooks to the ladder, and a block and a screw carried by each of said arms for adjusting said arms to rounds of different spacing.

4. Detachable ladder hooks, comprising parallel bars, having one end bent for gripping a round of a ladder, and having their opposite ends projecting beyond the end of the ladder, said ends bent to form sharp-pointed scaling-hooks adapted for attaching the ladder to another object, a swinging clamp disposed between, and intermediate the ends of said bars, adapted to grip the round nearest the end of the ladder for securing said bars to the ladder, means for pivotally connecting one end of said clamp to said bars, and means for locking the opposite end of the said clamp to said bars.

5. A pair of parallel arms having their upper ends formed into scaling hooks for clinging to a roof or window sill, and having their lower ends formed into securing hooks adapted to grip a round of a ladder, the said hooks arranged on the same side of said arms, and the said arms disposed parallel to each other and adapted to lie between the rails of the ladder, a swinging 10 clamp pivoted between said arms intermediate the said hooks, the said clamp having securing hooks adapted to engage an adj-

acent round of the ladder and to be swung into coincidence with said arms, for locking the said arms to the ladder, and a pair of 15 spring controlled latch-bolts for locking the clamp to the said arms.

In testimony whereof I affix my signature in presence of two witnesses.

HOWARD M. LUCAS.
